UNITED STATES PATENT OFFICE.

SAMUEL T. CRAWFORD, OF WASHINGTON, DISTRICT OF COLUMBIA.

COMB.

1,381,804.

Specification of Letters Patent. Patented June 14, 1921.

Application filed February 1, 1919, Serial No. 274,460. Renewed April 13, 1921. Serial No. 461,151.

To all whom it may concern:

Be it known that I, SAMUEL T. CRAWFORD, a citizen of the United States residing at Washington, in the District of Columbia, 5 have invented new and useful Improvements in Combs, of which the following is a specification.

This invention relates to combs and particularly that class adapted for use by barbers for cutting hair.

The primary object of the invention is to provide a comb of the class specified having a well balanced organization and a tooth structure and configuration to effectively 15 catch the hair and gradually and evenly raise it from the scalp to a degree in accordance with the length of the cut desired to be made. A further object of the invention is to form a barber's hair cutting comb 20 with a plurality of teeth having opposed concavo-convex edges whereby the teeth as a unit during operation will have an easy and regular fulcruming movement on their convex edges and an upper concave recess 25 formed by their concave edges for positive cutting application of shears therein. A still further object of the invention is to provide a comb having a plurality of teeth with opposed concavo-convex edges forming 30 as a unit, respectively, a convex fulcruming back and a concave cutting recess and being reversible to bring the free ends of the teeth in position for massaging the scalp and loosening and removing dandruff.

35 With these and other objects and advantages in view, the invention consists in the construction and arrangement of the several parts more fully hereinafter described and claimed.

40 In the drawing:—

Figure 1 is a perspective view of a comb embodying the features of the invention.

Fig. 2 is a top plan view of the comb.

Fig. 3 is a transverse vertical section on 45 the line 3—3, Fig. 2.

Fig. 4 is a transverse vertical section on the line 4—4, Fig. 2.

The numerals 5, 6 and 7, respectively, 50 designate the comb back, teeth and handle which are all preferably of integral construction, and in practice the comb as an entirety will be formed of some suitable light material, such as aluminum. Any material, however, may be used in the formation 55 of the comb. The back 5 is tapered regularly from its juncture with the handle

7 to its free end and has an outer substantially convex side 8 and an inner flat side 9, the teeth projecting from the flat side. By tapering the back 5 the thickness thereof 60 is gradually reduced toward its free end to effect a balancing action thereof when operated by the barber who grasps the handle 7. This handle 7 is also tapered toward its rear free end, the thickest part of the back 65 and handle being at their point of juncture adjacent to the innermost tooth 6. By this construction the back as a whole may be utilized as a fulcruming means to impart a partial rolling operation to the comb, or, by 70 proper manipulation of the handle, the comb may be tilted longitudinally and the thickest part of the back at the juncture thereof with the handle alone serve as the fulcrum. These varying operations of the comb will be effected to accommodate the particular kind 75 of cut to be made or found necessary in general hair shearing and trimming operations.

The teeth 6 are all the same size and have broad bases 10 from which they converge to 80 the free pointed ends 11, the back edges 12 of the teeth being convex and facilitating the partial rolling operation of the comb, and the inner edges 13 being concave and providing an inner curved recess in which the 85 shears are disposed to cut the hair brought up between the teeth and extending above the said concave edges 13. The shears may be placed at any point along the concave edges 13 of the teeth in accordance with the 90 length of cut to be made. The length of cut of the hair will also be controlled by the engagement or position of the back edges 12 of the teeth relative to the scalp, it being obviously apparent that when the pointed 95 ends 11 of the teeth are close to the scalp that a shorter cut of the hair may be made than when the intermediate portions of the back edges 12 of the teeth engage the scalp and the pointed ends 11 are clear of the latter. The 100 teeth may be effectively used as means for massaging the scalp and loosening dandruff by reversing or overturning the comb so that the back edges 12 of the teeth are uppermost and their concave edges 11 in lower positions, 105 thereby providing a clearance at the bottom portions of the teeth in rear of their points or between the latter and the back 5 which will result in a more effective operation by clearing the hair that may be located between the teeth points and the back. In this 110 reverse position of the comb to effect a mas-

sage treatment of the scalp and loosening of dandruff, the comb will be held down flat with all the teeth in engagement with the scalp and a portion of the back 5 of the comb 5 will rest upon the hair. The treatment of the scalp and the hair by reversing the comb as just explained will also be effective in cleaning out loose hair clippings from the cut hair and bringing the same to the surface, the 10 loose or clipped hair being forced upwardly from the convex edges of the teeth.

The improved comb is also very advantageous in hair culture operations or treatments of the scalp without breaking the latter. It fructifies the scalp and encourages the growth of the hair, and the dandruff that is loosened is raised to the surface of the hair from which it may be easily removed by a brush. Subsequent to shampoo or other 15 moisture treatment of the hair the improved comb will be found effective in drying the hair. Moreover, it will be seen that the teeth of the comb are relatively close, or, separated by very narrow spaces, and as a consequence 20 will serve more efficiently in hair cutting operations by bringing up and holding hair in closely confined locks or portions.

The teeth of the comb are formed in a strong and durable manner so that they can 30 not be readily broken or distorted, and in view of the greatest width of the teeth being located adjacent to the back or formed at the point of juncture of the teeth with the back, the said teeth may be constructed relatively 35 thin and will be materially reinforced against fracture. It will also be understood that the teeth may be arranged as close or

as far apart as desired and as may be found advantageous. Furthermore, the comb may be readily cleaned or sterilized and maintained in hygienic condition, and it may be made in various sizes. 40

What is claimed is:—

A comb of the class specified having a back extending from a handle, the back tapering from the handle portion to the front end of the comb and having a rear convex side and a front longitudinally straight flat side, a plurality of teeth all of equal length projecting from the front flat side of the 50 back and having lower convex sides merging regularly into the said convex rear side of the back to provide a smooth rolling surface formed by the combined lower edges of the teeth and the rear side of the back, the teeth 55 tapering toward their free ends and having upper uniform concave edges to provide a concave recess throughout the series of the teeth for application in said recess of cutting shears, the tapering back gradually reduced 60 toward its free end effecting a balancing action of the comb when the latter is operated by gripping the handle and whereby the comb may also be tilted longitudinally and the thickest part of the back at the juncture 65 with the handle serving alone as the fulcrum for operating the comb to permit varying length cuts to be made with the comb.

In testimony whereof I have hereunto set my hand in presence of a subscribing witness. 70

SAMUEL T. CRAWFORD.
